UNITED STATES PATENT OFFICE.

TIPTON H. LUDLOW, OF CHANDLER, ARIZONA.

MEANS FOR OPERATING CASEMENT WINDOWS.

1,409,459.

Specification of Letters Patent. Patented Mar. 14, 1922.

Application filed April 16, 1921. Serial No. 461,852.

To all whom it may concern:

Be it known that I, TIPTON H. LUDLOW, a citizen of the United States, residing at Chandler, in the county of Maricopa and State of Arizona, have invented certain new and useful Improvements in Means for Operating Casement Windows, of which the following is a specification.

This invention relates to means for operating casement windows and embodies improvements on earlier devices of that character which employ a screw and links or levers operated thereby.

My improvements embody a novel combination of screw, traveling nut, push link or bar, swinging guide of peculiar form and special function, and a pushing and pulling connection between the link and the sash or window.

The invention, still further, embodies the arrangement of the operative parts in a box or case insuring that when the device is applied to the weight box or casing in proper position and connected to the window, it will necessarily operate accurately and satisfactorily.

The invention still further embodies means whereby the length of the stem of the operating crank may be adjusted, within certain limits, to different widths of window stools without necessitating change in the size of the crank but, of course, where the window has an extra width stool it will be necessary to use extra long crank stems.

One of the novel features of my invention is the bell crank shaped swinging guide which is pivoted at one end and at its other end connected to the push bar or linkage which connects the nut to the window. This improved feature insures correct guidance without any possibility of binding of the parts, and yet enables the operative parts to be contained within a small, very compact, box or casing which may be set in the weight space box back of the window jamb.

My improved mechanism is self-locking so that the window remains closed, open, or in any intermediate position to which it may be set by turning the crank, without having to resort to any extraneous locking means.

My improvements overcome what have, in practice, been serious defects in casement window operating means of which I have knowledge.

In the accompanying drawings:
Figure 1, is a detail horizontal section

through the weight space box, casing, and sash of a casement window, showing my invention installed and partly in section and dotted lines;

Fig. 2, is a vertical section through Fig. 1;

Fig. 3, is a view like Fig. 3, taken at right-angles thereto; and

Fig. 4, is a front elevation.

The casement window 1 is suitably hinged at 2. At any height of the window, for instance at the bottom of the sash or midway the height thereof, it is provided with a push bar 3 of any desired length. This may be contained within a hole or bore in the sash 1 if at the bottom of the latter, or, the bar may be screwed onto the face of the sash or window 1 if midway the height thereof and in that event be exposed on the inside of the window. This bar is used for the purpose of taking up the pushing and pulling strains incident to the use of the opener constituting the present invention.

My improved mechanism is contained within a box 4 which is small, flat, and compact. In practice this box will approximate dimensions of $4\frac{1}{8}'' \times 2\frac{1}{8}''$ setting which is set into the weight space box 5 back of the window jamb 6.

The bottom of the casing or box 4 has a depending trough or guide 7 in which travels and is guided against turning, the nut 8 whose movement causes the window to be opened or closed.

A screw 9 extends lengthwise of the trough-shaped guide 7 and on this screw works the nut 8. The screw is journaled in the casing 4 at its end 10 and also in a bushing 11 which is set in the face of the casing 4, the mounting of the screw preventing it from coming out of position. The end of the screw is provided with a squared part 12 on which is slipped a sleeve 13 which is adapted to turn in the window casing 14 and, in turn, receives the squared end of a crank 15. By this means accommodation is provided, within certain limits, for different thicknesses of the casing 14 but where the window stool is of unusual size it will be necessary to use a crank having a longer stem.

To fit the box 4 in position and insure correct adjustment so that there will be no binding of the operative parts and to insure the exactness of distances between pivots that is necessary to afford proper clearance, there is provided a boxing or shell 16. The shell 16 is provided with a plate 17 riveted thereto

at 18 and provided with adjustable slot and bolt connections 19 to the box 4. A separator or spacer 20 maintains the boxing 16 in proper relation to the box 4, there being a bolt 21 passing through said separator and connecting the box 16 to the box 4. An anchor and adjusting plate 22 serves to limit the swing of the sash.

The nut 8 is provided with a lug 23 having a nut and on which is pivoted a push bar 24 which has a forked end 25. Another push bar or link 26 is pivoted in between the jaws on the fork 25 on a pin 27. The forked end 28 of the push bar 26 is pivoted at 29 to the end of the bar 3.

A bell crank lever 30 which is pivoted on a rivet 31 to the box 4, has its other end pivoted to the pin 27. This bell crank lever is so arranged that when the nut 8 is at the outer end of the trough 7 and the casement window 1 is closed, one leg of the lever 30 will be disposed crosswise of the screw 9 and the other leg parallel thereto so that the bell crank lever may swing freely to bring its respective legs in reverse position relative to the length of the screw. The bell crank lever guide 30 during its movements serves as a guide which fixes and determines the arcuate path in which the pivot 27 must swing. Consequently there is no possibility of binding or jamming of the parts and, further, the use of this member 30 permits a very compact arrangement of the elements which would otherwise be difficult to attain if ease and accuracy of action are accomplished. I thereby overcome serious defects heretofore incident to the use of casement window oper-

ating devices employing screws, nuts and levers and obtain a powerful easily operating and simple mechanism which insures proper 40 operation and is at the same time self-locking so that the window will remain where set whether it be closed, open, or in any intermediate position.

My construction, being unitary so far as 45 the operating means is concerned, is easily set in position even by more or less unskilled labor.

I claim:

1. In a casement window operator, the 50 combination with a screw, of a movable member operated thereby, a linkage comprising articulated push bars pivoted to the movable member and to the window, and a bell crank lever having a pivotal mounting and 55 also pivotally connected to the linkage where the component members thereof are pivoted together, said bell crank lever constituting a guide which predetermines the path of travel of members of said linkage. 60

2. In a casement window operator the combination with a box having a guide trough, of an operating screw mounted in the box, a nut working on the screw and slidable in the guide trough, a linkage comprising 65 component members pivoted together one of which is pivoted to the nut and the other being adapted to be pivoted to the window, and a bell crank guide pivoted to the box and to the pivotal connection of the push 70 bars with each other.

In testimony whereof I affix my signature.

TIPTON H. LUDLOW.
